UNITED STATES PATENT OFFICE

118,244

DESIGN FOR A PHONOGRAPH CABINET OR SIMILAR ARTICLE

Arthur Nagel, Cleveland Heights, Ohio

Application August 9, 1939, Serial No. 86,566

Term of patent 3½ years

To all whom it may concern:

Be it known that I, Arthur Nagel, a citizen of the United States, residing at 3486 Tullamore Road, in the city of Cleveland Heights, county of Cuyahoga and State of Ohio, have invented a new, original and ornamental Design for a Phonograph Cabinet or Similar Article, of which the following is a specification, reference being had to the accompanying drawing, forming a part thereof,

The figure is a perspective view of the phonograph cabinet, the dominant features of which are shown in solid lines. The back of the cabinet is plain and the left side is the same as the right side.

I claim:

The ornamental design for a phonograph cabinet or similar article, substantially as shown and described.

ARTHUR NAGEL.
